UNITED STATES PATENT OFFICE.

OSCAR WOODWARD, OF BABYLON, NEW YORK, ASSIGNOR TO REMINGTON TYPE-WRITER COMPANY, OF ILLION, NEW YORK, A CORPORATION OF NEW YORK.

TYPEWRITING-MACHINE.

1,342,489.

Specification of Letters Patent. Patented June 8, 1920.

Application filed February 24, 1919. Serial No. 278,657.

To all whom it may concern:

Be it known that I, OSCAR WOODWARD, a citizen of the United States, and resident of Babylon, in the county of Suffolk and State of New York, have invented certain new and useful Improvements in Typewriting-Machines, of which the following is a specification.

My invention relates to typewriting machines and more particularly to means for controlling the dog carrier.

One of the main objects of my invention, generally stated, is to provide highly efficient means of the character specified.

More specifically considered the main objects of the invention are to provide highly efficient means for effecting control of the escapement mechanism from the space key; to combine in an efficient manner such means with the means for controlling the escapement from the printing means; to provide efficient means whereby the normal position of the space key and its points of arrest may be varied at will without affecting the control of the escapement by the space key; to provide means for noiselessly arresting parts of such controlling mechanism; to provide means whereby the parts may be quickly and effectively assembled, and easily detached and removed when desired; and to provide efficient means by which relative adjustments between the parts may be effected to compensate for variation that may be found in different machines, or different requirements in the use of such machines.

To the above and other ends which will hereinafter appear my invention consists of the features of construction, arrangements of parts and combinations of devices set forth in the following specification and particularly pointed out in the annexed claims.

In the accompanying drawings, wherein like reference characters represent corresponding parts in the various views,

Figure 1 is a fragmentary fore and aft vertical central sectional view of a sufficient number of parts of one form of typewriting machine to illustrate my invention in its embodiment therein.

Fig. 2 is a fragmentary detail perspective view showing a part of the escapement controlling mechanism.

Fig. 3 is an enlarged detail fragmentary side view illustrating the adjustable means

in the train of connections from the space key.

Fig. 4 is a like view of the same showing a different adjustment of the parts.

Fig. 5 is a transverse sectional view of the same taken on the line $x-x$ of Fig. 3 and looking in the direction of the arrow at said line.

Fig. 6 is a fragmentary detail rear elevation partly in section showing a modified form of returning spring for the space key connections.

Fig. 7 is a detail rear elevation partly in section and showing the universal bar and some of the connections to the dog carrier or rocker.

Fig. 8 is a detail perspective view of one of the padded brackets or stops for arresting the space key.

Fig. 9 is a detail perspective view of the adjustable plate or connecting device controlled from the space key.

Fig. 10 is a fragmentary rear elevation partly in section and showing the space key and the adjustable means for noiselessly arresting it.

Fig. 11 is a detail fragmentary side view illustrating a still further modification of the returning spring for the space key and connections, and the means for mounting and connecting said spring.

Fig. 12 is a detail fragmentary front view of some of the parts shown in Fig. 11.

Fig. 13 is an enlarged detail fragmentary front view with parts in section of some of the members shown in Figs. 11 and 12.

The frame of the machine comprises a base 1, corner posts 2 and a top plate 3. A suitably mounted power driven carriage travels over the top plate of the machine and carries a platen 4. The step-by-step feed movement of the carriage is controlled by an escapement wheel 5 as indicated for example in the patent to George A. Seib, No. 1,289,934 dated Dec. 31, 1918. The escapement wheel is under control of a loose dog 6 and a fixed dog 7, both carried by a dog carrier or rocker indicated as a whole by the reference numeral 8. The construction of the dog rocker and the parts carried thereby is the same, or substantially the same, in the present instance, as the corresponding parts in the aforesaid Seib patent and which will be hereinafter more specifically referred to.

Each printing key 9 is carried by a key lever 10 connected at 10^a to an angular sub-lever 11 fulcrumed at 12 to a cross bar 13 secured to the base of the machine. The 5 upper end of each sub-lever carries a laterally extending pin 14 received in a slot 15 in the heel of the associated type bar 16. The segmentally arranged type bars are mounted on a pivot wire 17, carried by a 10 type bar segment 18 and are adapted to move upwardly and rearwardly and strike against the front face of the platen 4. Each type bar works in the guide slot in the type bar segment, and is provided with a contact 15 edge 19 which coacts with a segmental universal bar 20 and moves the same rearwardly as a type bar approaches the printing position. The universal bar is provided with a lug 21 which carries a guide pin 22 20 that extends forwardly through a guide opening in the type bar segment. Projecting rearwardly from the universal bar are two integral arms 23 pivoted at their rear ends, as at 24, to upright crank arms 25 25 which extend upwardly from a rock shaft 26. This shaft is supported at its ends by coned pivot screws 27 held in depending arms 28 secured to the top plate of the machine.

30 A centrally disposed crank arm 29 extends upwardly from the rock shaft and is forked at its upper end, as at 30. A pin 31 extends between the two arms of the fork 30 and is received in an open-ended slot 32 35 in the forward end of a link 33. The forward forked end of the link 33 is thus received and guided in the slot formed between the arms of the fork 30, and is supported by the pin 31. This pin is normally 40 seated against the bottom wall of the slot 32, so that a rearward movement of the crank arm 29 is effective to transmit a corresponding movement to the link 33. The rear end of this link is likewise forked as indicated 45 at 34, the prongs of the forks at opposite ends of the link extending in opposite directions. The rear fork straddles the shank of a headed pin 35 which projects laterally from a depending arm 36 adjustably secured 50 to the dog rocker, as fully shown and described in the above mentioned Seib patent. Thus, the arm 36 is pivoted to the dog rocker at 37 above the pivots 38 of the latter, and may be adjusted to different angular 55 positions around said pivot 37 and secured in its adjusted position by a set screw 39.

The movements of the dog rocker around its pivots 38 to and from normal position 60 are limited by the set screws or stops 40 and 41 respectively, said stops co-acting with corresponding stop faces on the bracket 42 from which the dog rocker may be detached by loosening one of the screws 43 and with- 65 drawing the associated coned pivot pin 38.

As pointed out in the said Seib patent the purpose of the above mentioned adjustment of the arm 36 is to compensate for any variation that there may be in different machines in the train of connections intermediate the universal bar and dog rocker, and to properly regulate the "pull" on the dog rocker in each machine.

In order to return the dog rocker, the universal bar, and the intermediate operative 75 connections between the two, to normal position, a contractile spring 44 is connected at one end to a bracket arm 45, and at its opposite end to a screw 46 threaded into a tapped opening in the hub of the dog rocker. 80

A depression of a printing key is effective, through the associated type bar, to actuate the universal bar, the members 25-26-29, 33 and the dog rocker 8, such parts being returned to normal position by the reaction 85 of the spring 44 when the printing key is released, and a letter space feed of the carriage is thus produced.

The escapement is controlled from the space key 47 by a separate train of connections which extends from said space key up to and coacts with the link 33, and includes certain adjustable devices as will now be pointed out. The space key 47 is connected at each end to a rearwardly extending crank 90 arm 48 secured to a rock-shaft 49 mounted at its ends on screw pivots in the base of the frame. The space key 47, arms 48 and rock shaft 49 thus in effect constitute a rectangular pivoted frame. A centrally disposed upwardly and rearwardly extending two-part crank arm or member, designated as a whole by the reference numeral 50, projects from the rock-shaft. This crank arm comprises a part 51 fixedly secured to the 95 rock shaft, and preferably formed as a forging with an enlargement 52, as shown. The second part of the crank arm comprises a sheet metal plate-like member 53 pivotally connected at one end, as at 54, to the arm 51. 100 The upper end of the member 53 extends beyond the end of the arm 51 as a prolongation thereof, and carries at its upper end a laterally projecting headed pin 55. In order that the member 53 may be adjusted 105 around its pivot 54, and held against accidental displacement relatively to the arm 51, I have constructed the parts as follows: The member 53 is formed with a radial slot 56 therein. A screw 57 is formed with an 110 eccentric head 58, the stem of the screw being received in a tapped opening in the part 52, whereas, the head of the screw is received in the slot 56, the diameter of the head corresponding to the width of the slot. 115 An adjustment of the screw or eccentric from the Fig. 3 to the Fig. 4 position is effective to adjust the member 53 in one direction from the central position (shown in Fig. 3) around the pivot 54. An adjust- 120 125 130

ment of the screw 57—58 in the opposite direction is effective to bring about a corresponding adjustment of the member 53 in the opposite direction. In order to hold the member 53 in its adjusted position relatively to the arm 51, said member is provided with a segmental slot 59 formed in an arc of which the pivot 54 is the center. The stem of a headed binding screw 60 passes through 10 said slot and is received in a tapped opening in the member 51. The head of the binding screw is adapted to bear against the outer side of the part 53 when the screw is turned in, and to bind said member against 15 the side face of the part 52, thus holding the part 53 against movement around its pivot 54.

The headed pin 55 is straddled by the lower forked end 61 of a lever 62. This 20 lever is apertured to receive a shouldered pivot screw 63, threaded into a hub 64 which extends laterally from a bracket arm 65, secured by screws 66 to the top plate. The upper end of the lever 62 projects in front 25 of, and preferably normally in contact with, a laterally projecting lug 67 formed on the link 33.

The space key and the parts connected therewith are returned to normal position 30 by a suitable spring or springs. In the construction shown in Figs. 1 and 2 one end of a contractile spring 68 is connected to each of the crank arms 48, the opposite end of each spring being connected to a depending 35 pin 69 carried by a cross bar on the base of the machine.

In Figs. 6, 11 and 12 I have shown other forms of springs and means for mounting and connecting the same, as will hereinafter 40 appear.

It will be understood that a depression of the space key is effective to rock the shaft 49, and through the two-part crank arm 50, rock the lever 62 moving the upper end of 45 the latter rearwardly. The effect of this is to produce a rearward endwise movement of the link 33 to actuate the dog rocker. It will be understood that at this time the link 33 moves independently of the crank 50 arm 29, so that the latter and the parts intermediate said arm and the universal bar remain at rest, thus relieving the space key of the load of the universal bar and its connections back to the link 33.

It will also be understood that when the escapement is actuated from a printing key 9 as hereinbefore described, the space key and its entire train of connections up to the link 33 remain at rest, so that the load of 60 these parts is not borne by printing keys and offers no resistance thereto.

From an inspection of Figs. 1 and 2 it will be seen that a guide comb 70 is fixed to the base of the machine, and has the usual 65 guide slots 71 for coöperation with the key

levers of the printing keys 9. However, where the arms 48 of the space key pass through the guide comb enlarged spaces 72 are provided so that the side walls of spaces 72 are at all times maintained free from 70 contact with the arms 48, and lateral play of the arms will not bring them into contact with the comb, thus preventing rattling and enabling the space key to be noiselessly arrested as will hereinafter appear. 75

Referring particularly to Fig. 6, it will be understood that the returning springs 68, shown in Figs. 1 and 2, are replaced by a single wire spring 73 formed with a coil which passes around the hub 64, and at one 80 end 74 is hooked around one edge of the lever 62, whereas the opposite end 75 of the spring is hooked around one edge of the bracket 65. The reaction of this spring returns the lever 62 and the parts connected 85 therewith, including the space key to normal position.

The preferred form of returning spring and mounting is shown in Figs. 11, 12 and 13, from which it will be seen that a hub 76 90 is secured to the bracket 65 by a headed shouldered rivet 77 which constitutes the pivot for the lever 62. The hub is formed with a peripheral substantially V-shaped groove 78 therein which occupies substantially the entire widthwise dimensions of the hub. The hub maintains the lever spaced apart from the arm of the bracket 65 and forms a bearing for a wire returning spring 79. The spring intermediate its ends is 100 formed with an arc-like portion 80, the curvature of which conforms substantially to the curvature of the hub at the bottom of the groove 78 in which the spring is seated. The upper end of the spring is formed with 105 a hook 81 adapted to engage around one edge of the arm of the bracket 65. The opposite end of the spring is bent at 82, as best shown in Fig. 12, and said bent end is passed through an opening 82^a in the lever 110 62. This construction is such that the spring may be readily connected to the associate parts and mounted in place, and may as readily be detached when desired. It will be understood that the grooved hub constitutes a centering device, for properly maintaining the spring centered in the space between the lever 62 and the arm of the bracket 65, where it will not interfere with the operation of the lever or the link 33. Any tendency toward an accidental lateral displacement of the spring is resisted by the walls of the grooved hub in which it is seated. 115

The character of the operator's touch often determines the desired normal height of the 125 space key with reference to the first row of printing keys, and also in some instances determines the extent of "dip" which the space key should have. One such position of the space key is shown in Fig. 1. Some oper- 130

ators by reason of peculiarities of touch may desire a normally lower space key, or a different extent of dip for most effective work. According to my present invention the normal height of the space key may be regulated as desired, the depth of dip of the space key may be also regulated, and the space key may be noiselessly arrested in both its down stroke and up stroke. Thus, upon reference to Figs. 1, 2, 8 and 10 it will be seen that a short metal bracket or stop, designated as a whole by the reference numeral 83, is secured beneath the space key by screws 84 near each end thereof. Each bracket 83 comprises a base 85 secured to the space key, a depending arm 86, and an arm 87 which is inclined downwardly and outwardly and in a general direction longitudinally of the space key. The arms 87 are oppositely disposed and provide oppositely inclined contact faces on the upper sides thereof which tend to exert a wedging action in opposite directions, as will hereinafter appear. Co-acting with each of the brackets 83 is a padded sheet metal bracket or stop, designated as a whole by the reference numeral 88 and shown in detail in Fig. 8. Each member 88 comprises a base 89 with slots 90 extending longitudinally thereof. The stems of the headed screws 91 pass through these slots and engage in tapped openings in the front cross bar of the base of the machine, while the heads of the screws bind against the base 89 of each bracket and hold it in the position to which it may be adjusted bodily in a straight line transversely of the machine. Attached to the base 89 of each bracket is an arm 92 the free end portion 93 of which is inclined upwardly and inwardly to match substantially the inclination of the part 87 of the co-acting bracket 83. The parts 93 are inclined in opposite directions transversely of the machine and in a general direction longitudinally of the space bar. Each part 93 has a pad 94, preferably of felt, secured thereto and received between the members 85 and 87 of the associated bracket 83. In the present instance each pad is bent around the end of the part 93 of the associated bracket and covers the top and bottom faces thereof, the pad being secured in place by a rivet 95. The down stroke of the space key is noiselessly arrested by the base 85 of each bracket striking the upper side of the coacting pad at 96, whereas the upstroke of the key is arrested by the upper inclined faces 87 of the stops 83 striking the correspondingly inclined lower faces of the pads 94. The oppositely inclined faces of the stops tend to exert a wedging action transversely of the machine, longitudinally of the space key and consequently transversely of the arms 48 which carry the space key, and in a plane parallel 65 with the axis of the rock shaft 49 which car-

ries the space key. For this reason there is no wedging action exerted transversely against the rock shaft 49 which might result in a rattling of the parts if the shaft be loose in its bearings. It will be understood that 70 the wedging action of one fixed stop 88 is resisted by the other fixed stop at the opposite end of the space key and that the construction is such that the arrest of the space key in its return movement is noiselessly effected, and that any undue rebound of the key is prevented.

The stock from which the brackets 88 are formed is of such a character that the arms 92 may be bent to raise or lower the pads 80 without changing or materially changing the inclination thereof. A change in the normal position of the space key may be effected by a bodily adjustment of the brackets 88 toward or away from each other 85 in a straight line. This in ordinary cases may give sufficient range of adjustment to determine the normal position of the key. If this range of adjustment is insufficient however, the arms 92 may be bent to raise 90 or lower the pads without changing, or materially changing the inclination thereof. With the bodily adjustment of the brackets 88 there would also be a change in the extent of dip of the space key. In order to avoid 95 this a bending of the arm 92 may be effected. In practice the arms 92 may ordinarily be bent to determine the point in the down stroke of the key where it is desired to arrest it, and then the brackets 88 may be adjusted 100 bodily toward or away from each other to determine the normal position of the key, or the point of arrest in its return movement. The bending of the arms 92 to raise or lower the pads does not change the extent 105 of dip but does change the normal position of the key and the point of arrest in its down movement. It will be understood thereby that the stop pads have two adjustments at right angles to each other, one an 110 up and down adjustment by bending the arms and the other a horizontal bodily adjustment with the brackets 88.

It has been explained in the hereinbefore mentioned Seib patent that the adjustment 115 of the arm 36 on the dog rocker is to compensate for various inaccuracies or variations in the trains of connections between the universal bars and dog rockers in different machines, and to give the proper "pull" 120 on the dog rocker. It will be understood that this adjustment requires a corresponding adjustment in the train of connections between the space key and the link 33. For example, any fore and aft adjustment of the 125 link 33 requires a corresponding adjustment of the upper end of the lever 62 to properly coact therewith. Moreover, any adjustment of the space key requires a corresponding adjustment in the train of connections inter- 130

mediate said key and the link 33, so that the upper end of the lever 62 will stand normally in the same relation to the lug 67 on the link 33 at all times. It is to meet 5 these different requirements therefore that the adjustable means disclosed in detail in Figs. 3 and 4 are provided, and so that the control of the escapement may be effected in a like manner from the space key that it 10 is from a printing key, although through two separate trains of connections and irrespective of the independent adjustments required in each train for conditions which are peculiar to each train.

15 From an inspection of Fig. 1 it will be seen that the link 33 normally extends above and out of contact with a ribbon spool shaft 97 which extends transversely across the machine. It will also be seen that the formation of the link 33 is such that it provides a shoulder 98 in front of said shaft. If for any reason it is found desirable to detach the dog rocker from the machine one of the screws 43 is backed up, the corresponding pivot 38 is moved back and the rocker may be removed, the pin 35 moving freely from the open ended slot or fork 34 in the link 33. At this time the rear end of the link is free to drop until the link bears 20 against the shaft 97. The shoulder 98 in the link will prevent it from being accidentally moved rearwardly far enough to detach the link from the arm 29, and prevent the link from being displaced out of 25 operative relation with the parts with which it coacts. The pin 35 may again be introduced into the fork 34 and the dog rocker replaced on its pivot pins 38. These and other features of the construction enable the 30 parts to be quickly and accurately assembled and facilitates replacement or repair.

What I claim as new and desire to secure by Letters Patent, is:

1. In a typewriting machine, the combination of type bars, a universal bar controlled thereby, a dog carrier, intermediate operative connections between said universal bar and dog carrier, a space key, a rock shaft to which said space key is connected, 45 and adjustable operative actuating connections between said space key and the connections intermediate the universal bar and the dog carrier.

2. In a typewriting machine, the combination of type bars, a universal bar controlled thereby, a dog carrier, intermediate operative connections between said universal bar and dog carrier that enable the universal bar to move the dog carrier and enable the dog carrier to be moved independently of the universal bar, a space key, a crank arm controlled thereby, operative connections intermediate said crank arm and a member of said first mentioned connections and including adjustable means

through which said member of the first mentioned connections and the dog carrier may be operated independently of the universal bar by an actuation of the space key.

3. In a typewriting machine, the combination of type bars, a universal bar controlled thereby, a dog carrier, intermediate operative connections between said universal bar and dog carrier, said connections including adjustable means, a space key, means for affording an adjustment of said space key, dog carrier actuating means controlled by the space key and including adjustable means for compensating for an adjustment of the space key and said first mentioned 70 adjustable means.

4. In a typewriting machine, the combination of a dog carrier; a space key; a rock shaft by which said space key is carried; a crank arm fixed to said rock shaft; and intermediate operative actuating connections between said crank arm and dog carrier including a member carried by and adjustable 75 on said crank arm.

5. In a typewriting machine, the combination of a dog carrier; a space key; a rock shaft by which said space key is carried; a crank arm fixed to said rock shaft; and intermediate operative actuating connections between said crank arm and dog carrier 90 including a member pivoted on said crank arm, and means for holding said member in the different set positions to which it may be adjusted on said arm around the pivot of said member.

6. In a typewriting machine, the combination of a dog carrier; a space key; and intermediate operative actuating connections between said space key and dog carrier, said connections including a pivoted member, an eccentric for adjusting said member to different set positions, and means for holding the member against accidental displacement from the position to which it is adjusted.

7. In a typewriting machine, the combination of a dog carrier; a space key; and intermediate operative actuating connections between said space key and dog carrier, said connections including a pivoted member 110 having a slot therein, an eccentric for adjusting said member to different set positions, and a headed binding screw which is received in said slot and holds the member against accidental displacement from the position to which it is adjusted.

8. In a typewriting machine, the combination of a dog carrier; a space key; and intermediate operative actuating connections between said space key and dog carrier, said 125 connections including a pivoted member having a radial slot and also an arc-like slot therein, an eccentric received in said radial slot for adjusting said member, and a headed binding screw received in said arc- 130

like slot for holding the member against accidental displacement from the position to which it is adjusted.

9. In a typewriting machine, the combination of a dog carrier, a space key, adjustable stop means for arresting the return stroke of said key and for affording an adjustment thereof to different normal positions, intermediate operative actuating connections between said space key and dog carrier, and means for effecting a relative adjustment between members of said connections to compensate for the adjustment of the space key.
10. In a typewriting machine, the combination of type bars; a universal bar controlled thereby; a dog carrier; intermediate operative actuating connections between said universal bar and dog carrier, said connections including adjustable means; a space key; adjustable stop means for arresting said key and for affording an adjustment thereof to different normal positions; and operative connections from the space key for actuating the dog carrier, said last mentioned connections including adjustable means for compensating for the adjustment of the space key and said first mentioned connections.
11. In a typewriting machine, the combination of type bars, a universal bar controlled thereby, a dog carrier, intermediate actuating connections between said universal bar and dog carrier including a link that is moved by said universal bar and is free to be moved independently thereof, a space key, and operative connections from said space key that coact directly with said link to move it and the dog carrier independently of the universal bar.
12. In a typewriting machine, the combination of type bars, a universal bar controlled thereby, a dog carrier, intermediate actuating connections between said universal bar and dog carrier including a link that is moved by said universal bar and is free to be moved independently thereof, a space key, a rock shaft controlled thereby, and intermediate operative connections between said rock shaft and link for moving the latter and dog carrier independently of the universal bar and for affording a movement of the link by the universal bar independently of the connections from the space key.
13. In a typewriting machine, the combination of type bars, a universal bar controlled thereby, a crank arm controlled by the universal bar and carrying a pin, a detachable dog carrier having a pin, a link forked at one end to co-act with the pin on the crank arm and forked at the other end to co-act with the pin on the dog carrier, whereby the dog carrier may be detached independently of said link, and means for preventing an accidental detachment of the link from said crank arm and for supporting the link in position for reattachment to the dog rocker.
14. In a typewriting machine, the combination of type bars, a universal bar controlled thereby, a crank arm controlled by the universal bar and carrying a pin, a dog carrier having a pin, a link forked at one end to co-act with the pin on the crank arm and forked at the other end to co-act with the pin on the dog carrier, a space key, and a crank arm controlled by said space key and coöperative with the link to move it and the dog carrier independently of the universal bar and to afford a movement of the link by the universal bar independently of the space key controlled crank arm.
15. In a typewriting machine, the combination of a universal bar, a dog carrier, an intermediate link forked at one end to co-act with a part controlled by the universal bar and forked at the other end to co-act with the dog carrier, a projection on said link, a space key, and an arm controlled by said space key and coacting with the projection on the link.
16. In a typewriting machine, the combination of a space key, a rock shaft which carries said space key, a crank arm carried by said rock shaft, an upright lever controlled by said crank arm, and a dog carrier distinct from but controlled by said lever.
17. In a typewriting machine, the combination of a space key, a rock shaft which carries said space key, a crank arm carried by said rock shaft, a lever controlled by said crank arm, a link controlled by said lever, and a dog carrier controlled by said link.
18. In a typewriting machine, the combination of a space key, a rock shaft which carries said space key, a crank arm carried by said rock shaft, a lever controlled by said crank arm, a link controlled by said lever, a dog carrier controlled by said link, a universal bar, and independent connections therefrom for controlling said link.
19. In a typewriting machine, the combination of a space key, a rock shaft which carries said space key, a crank arm carried by said rock shaft, a lever controlled by said crank arm, a link controlled by said lever and so operatively connected therewith as to afford a movement of the link independently of said lever, a dog carrier controlled by said link, a universal bar, and independent connections therefrom for controlling said link, said independent connections including means for permitting an actuation of the link by the space key independently of the universal bar.
20. In a typewriting machine, the combination of a space key, and means for noise-

- lessly arresting both the downstroke and the upstroke of said space key, said means comprising a set of two brackets having oppositely inclined contact faces, and a second 5 set of two co-acting brackets having oppositely inclined padded arms which co-act with the first mentioned brackets, each pad serving to cushion both the down stroke and the up stroke of the space key.
- 10 21. In a typewriting machine, the combination of a space key, and means for noiselessly arresting both the downstroke and the upstroke of said space key, said means comprising a set of two brackets having oppositely inclined contact faces, a second set 15 of two co-acting brackets having oppositely inclined padded arms which co-act with the first mentioned brackets, and means for affording an independent relative adjustment between the brackets of one set.
22. In a typewriting machine, the combination of a space key, and means for noiselessly arresting both the downstroke and the upstroke of said space key, said means comprising a set of two brackets having oppositely inclined contact faces, a second set 25 of two co-acting brackets having oppositely inclined padded arms which co-act with the first mentioned brackets, and means for affording a rectilinear bodily adjustment between the brackets of one set toward and away from each other.
23. In a typewriting machine, the combination of a space key, and means for noiselessly arresting both the downstroke and the upstroke of said space key, said means comprising a set of two brackets having oppositely inclined contact faces, a second set 30 of two co-acting brackets having oppositely inclined padded arms which co-act with the first mentioned brackets, the contact portion of each bracket of one set being individually adjustable up and down, and means for affording a relative rectilinear 35 bodily adjustment between the brackets of this same set toward and away from each other.
24. In a typewriting machine, the combination of a space key, and means for noiselessly arresting both the downstroke and the upstroke of said space key, said means comprising a set of two brackets carried by the space key and having oppositely inclined contact faces, each of which 40 extends downwardly and outwardly toward a side of the machine, and a second set of co-acting brackets carried by the frame of the machine and having oppositely inclined padded arms which coact with the brackets 45 on the space key, the said arm of each bracket of the second set being inclined upwardly and inwardly toward the center of the machine.
25. In a typewriting machine, the combination of a space key, and means for noise- 50 lessly arresting both the downstroke and the upstroke of said space key, said means comprising a set of two brackets carried by the space key and having oppositely inclined contact faces, each of which extends downwardly and outwardly toward a side of the machine, and a second set of co-acting brackets carried by the frame of the machine and having oppositely inclined padded arms which coact with the brackets on the space key, the said arm of each bracket of the second set being inclined upwardly and inwardly toward the center of the machine, and means for affording a relative adjustment of the brackets of the one set toward and away from each other.
26. In a typewriting machine, the combination of a space key, and means for noiselessly arresting both the downstroke and the upstroke of said space key, said means comprising a set of two brackets having oppositely inclined contact faces, and a second set of two coacting brackets having oppositely inclined padded arms which coact with the first mentioned brackets, each padded arm extending between two arms of a bracket of the other set, the coöperating inclined contact faces coacting to limit the stroke of the space key in only one direction.
27. In a typewriting machine, the combination of a space key and means for noiselessly arresting both the downstroke and the upstroke of said space key, said means comprising a set of two brackets having oppositely inclined contact faces, and a second set of two coacting brackets having oppositely inclined padded arms which coact with the first mentioned brackets, the coacting inclined contact faces tending to exert a wedging action longitudinally of the space key only on the upstroke of the latter, one set of brackets resisting the wedging action of the brackets of the other set.
28. In a typewriting machine, the combination of arms which extend fore and aft of the machine; a space key carried by said arms; and means for arresting the upstroke of said space key, said means comprising a wedging contact face carried by the space key, and a stop carried by the frame of the machine and having a coöperative wedging contact face, the coöperative inclined or wedging contact faces being so disposed as to exert a wedging action transversely of the arms and longitudinally of the space key, substantially as and for the purposes specified.
29. In a typewriting machine, the combination of a pivoted member, a support therefor, a spring connected at its ends to said member and support, and a separate fixed centering device coöperative with said spring intermediate its ends to prevent a lateral displacement of said spring and hold

said intermediate portion away from said pivoted member.

30. In a typewriting machine, the combination of a pivoted actuating member, a grooved centering device adjacent to the pivot of said actuating member, and a spring seated intermediate its ends in the groove of said centering device and connected at one end to said member and at its 10 opposite end to a fixed point.

31. In a typewriting machine, the combination of a bracket arm, an actuating member pivoted to said bracket arm, a peripherally grooved hub carried by said 15 bracket arm intermediate said arm and member at the pivot of the latter and maintaining the two spaced apart, and a spring which extends between said arm and mem-

ber and intermediate its ends is seated in the peripheral groove in the hub, one end of the 20 spring being connected to said arm and the other end to said member.

32. In a typewriting machine, the combination of a space key, two upwardly and oppositely inclined fixed pads, and two 25 downwardly and oppositely inclined contact devices depending from said space key and extending under said pads.

Signed at the borough of Manhattan, city of New York, in the county of New York, 30 and State of New York, this 20th day of February, A. D. 1919.

OSCAR WOODWARD.
